UNITED STATES PATENT OFFICE.

FRANK R. CHESTER, OF NEW YORK, N. Y.

TELEPHONE-DIRECTORY DEVICE.

1,332,604.

Specification of Letters Patent.

Patented Mar. 2, 1920.

Application filed March 6, 1919. Serial No. 280,975.

To all whom it may concern:

Be it known that I, FRANK R. CHESTER, a citizen of the United States, residing at New York, in the State of New York, have 5 invented certain new and useful Improvements in Telephone-Directory Devices, of which the following is a specification.

This invention relates to new and useful improvements in telephone directory devices.

The purpose of the invention is to provide a convenient and compact means of listing names and numbers such as are frequently called, and adapted to be attached to the 15 telephone instrument so as to be readily manipulated to display a desired number.

In carrying out the invention a disk is provided with radial spaces for writing therein the names of parties frequently 20 called or whose names and numbers are desired for a particular purpose. A correlated disk cover by the first disk is exposed through a slot in the latter. Sufficient of the second disk is exposed to contain a telephone number. The name disk is fixed 25 while the number disk is rotatable. An indicator carried by the number disk overhangs the name spaces of the name disk and by rotating the number disk so that the 30 indicator is brought to a name the number of this party is displayed through the slot or if the number has not been written on its disk it may be written and will be displayed at future operations.

35 It will be at once apparent that by the use of two disks a greater number of names may be written on the name disk as no space is necessary for the numbers which are written separately on the number disk. The 40 diameter of the device may be kept within reason by the use of two disks and some space is left on the name disk for other purposes.

The invention will be more readily understood from a reading of the following 45 specification and by reference to the accompanying drawings, in which an example of the invention is shown and wherein:

Figure 1 is a front elevation of the device,

Fig. 2 is a rear elevation, and

Fig. 3 is a diametrical sectional view of the device showing it fastened on a transmitter by the mouth-piece.

55 In the drawings the numeral 10 designates

an annular metal frame having an open face and quadrilateral ribs 11 bisected by an integral ring 12 and radiating from a central ring 13. This provides four segmental openings 14 between the ring 12 and the 60 margin of the frame and a similar number of openings 15 between the rings. The ring 13 has a collar 16 within the frame. A name disk 17 of cardboard or other suitable material is fitted snugly into the frame so as 65 to surround the collar and fit the inner face of the annular flange 18 of the frame, which face may be suitably roughened for this purpose. The face of the disk is thus displayed at the openings 14 and 15. Within the openings 14 the disk 17 is provided with radial spaces or panels 17'; while within the openings 15 advertising or other matter may be printed.

A circular metal back plate 19 is mounted 70 to rotate on the collar 16 within the frame and is provided with four equally spaced lugs 20 which overhang the flange 18 and bent upon themselves with their ends 21 bearing on the margin of the face of 75 frame and serving to hold the frame and the back plate together. One of the lugs carries an index 22 on its end 21 adapted to register with the spaces 17'. The collar 16 may be secured to a transmitter A 80 by a mouth-piece B, thus holding the frame and name disk 17 stationary. Each lug 20 serves as a finger rest for the operator who uses the most convenient one and pulls down 85 thereon to rotate the back plate 19. 90

A number disk 23 of substantially the same diameter as the disk 17 is fastened to the inner face of the plate by bending opposed ears 24 over the same. This disk 23 is rotated with the plate. The right hand rib 95 11 has a slot 25 in its portion separating the adjacent openings 14. The disk 17 also has a slot 26 registering with the slot 25. The disk 23 is thus visible through the slots and is used for telephone numbers. 100

In arranging or preparing the disks the name of a party as "J. Doe" is written in one of the spaces 17' and the plate 19 rotated so as to bring the index 22 to register with this space as is shown in Fig. 1. The 105 number of this party which may be "M-348" is written on the number disk 23 through the slots. Other names and numbers are written in the same manner. It is obvious that when a number is wanted it is 110

- merely necessary to rotate the plate until the index registers with the space bearing the name of the party, whereby the disk 23 is rotated to bring the number into view
- 5 through the slots. Names and numbers may be added as desired. By bending the lugs 20 and ears 24 the parts may be disassembled and new names and number disks inserted. The three ribs 11 other than that having the slot 25 may contain the emergency calls, such as the fire department, ambulance and police, or some other special designation, the number being printed on the disk 23 so as to appear through the slots.
- 10 15 What I claim, is:
- In a telephone directory device; an outer relatively stationary frame embodying an outer ring carrying a laterally extending flange, an inner hub to be clamped to the transmitter of the telephone, and radial ribs connecting the hub and outer ring, said radial ribs forming segmental name openings, and one radial rib being provided with a number opening; a name disk adapted to be held stationary within the outer

frame by engaging within the annular flange thereof, said name disk being adapted to be removed when desired and having portions for receiving names which are visible through the name openings, said name disk being provided with a number opening in registration with the first named number opening; a back plate having an opening to pivotally receive the hub of the outer frame so that such back plate may be turned with relation thereto, the back plate being spaced from the name disk, said back plate being provided at its periphery with radial lugs bent to form sockets which slidably embrace the flange of the outer frame, one socket having a pointer to coact with the name disk; and a number disk arranged within the flange of the outer frame and secured to the back plate for rotation therewith, said number disk having numbers to be brought to a position to be viewed through said number openings.

In testimony whereof I affix my signature.

FRANK R. CHESTER.
